DREDGE FOR MINING

Bert O. Godfrey, Brooklyn, N. Y.

Application September 17, 1938, Serial No. 230,425

4 Claims. (CL. 37—61)

This invention relates to new and useful improvements in dredges.

The invention particularly relates to an improvement of my Patent No. 1,461,240 patented on July 10, 1923, and entitled "Dredge."

The invention relates to the construction of the conduits which extend through a body of water, such as a stream, and into the mud, sand, gravel or the like at the bottom of the body of water. The patented invention discloses the provision of a certain nozzle space between the conduits used in the device. The present invention relates to the construction of the conduits in a manner so that the nozzle space may be adjusted and controlled.

Furthermore, the invention proposes constructing the conduits of more or less standard pipe fitting connections, and altering certain of these connections in minor respects to adapt them for the purpose desired.

Still further the invention proposes the provision of an indicator associated with the device in a manner so that the size of the nozzle passage may be readily known and controlled when required.

Another object of this invention resides in the provision of locking elements arranged in a novel manner for locking certain portions of the conduit to control the nozzle passage.

Still further the invention proposes several embodiments and modifications which will be useful for facilitating digging and dredging and for facilitating assembling and taking down of the device. This will become clearer as the specification proceeds.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a dredge constructed according to this invention.

Fig. 2 is a plan view of Fig. 1.

Fig. 3 is a vertical sectional view of the article shown in Fig. 1, with a certain auxiliary bottom hollow body added thereto.

Fig. 4 is a horizontal sectional view taken on the line 4—4 of Fig. 3.

Fig. 5 is a perspective view of a device constructed according to a modification of the invention.

Fig. 6 is a fragmentary sectional view of the bottom portion of Fig. 5.

Fig. 7 is a fragmentary vertical sectional view of a device constructed according to another embodiment of this invention.

Fig. 8 is a vertical sectional view of a device constructed according to a still further embodiment of the invention.

Fig. 9 is a vertical sectional view illustrating a still further modification.

The dredge, according to this invention, includes a valve controlled vertical inner conduit 10 having an internal upwardly and inwardly tapered bottom end portion 11. An elbow 12 has a portion of the inner conduit 10 engaged through the vertical arm thereof. A nut 13 is fixedly mounted on the extended end of the inner conduit 10 and is threadedly engaged into the top end of the vertical arm of the elbow 12 for holding the inner conduit in various adjusted positions with respect to the elbow. An outer conduit 14 is fixedly threadedly connected with the bottom end of the vertical arm of the elbow 12 coaxially of the inner conduit, and encases the same. A hollow body 15 is mounted upon the bottom end of the outer conduit. A hollow tip 16 is adjustably mounted coaxially through the bottom of the hollow body 15 and has an upwardly tapered upper end portion 17 cooperative with the tapered bottom end portion 11 for forming a passage in the form of a zone of a cone to act as a suction nozzle. A nut 18 is threadedly mounted on the tip 16 and is adapted to abut the bottom end of the hollow body 15 for fixedly holding the tip.

The valve controlled inner conduit 10 is provided with a valve 20 at an upper portion thereof. This valve is operated by a handle 21. The handle 21 is mounted on a pintle 22 which connects with the valve head 23 and serves to pivotally support the valve head. When the handle 21 is moved it is possible to pivot the valve head 23 to a position to close the passage through the valve. The valve body 20 is provided with an offset body portion 20^a into which the valve head 23 normally reposes when the valve is in an open position.

While this particular type of valve is shown, it should be understood that any other type may be used. The top of the valve body 20 is provided with threads 20^b adapted to receive a conduit, not disclosed in this specification, as this arrangement would be the same as in the prior patent. The horizontal arm 12^a of the elbow 12 is adapted to be connected with a fluid pump.

similar to that described in the prior patent and for this reason duplication of the description will be omitted from this specification.

The outer conduit 14 is formed from several sections which permit assembling and disassembling when required. There is an upper section 14^a and a lower section 14^b. These sections are locked together by a holding screw 24. The hollow body 15 is secured upon the bottom of the lower section 14^b by a holding screw 25. The arrangement is such that there is a definite space relationship between the inner conduit 10 and the hollow body 15. An indicator pointer 26 is mounted upon the upper end of the inner conduit 10, above the nut 13, and extends over a portion of the elbow 12 and operates across a scale 27 imprinted upon the elbow. This indicator 26 is useful in indicating the space relationship between the inner conduit 10 and the hollow body 15. The hollow tip 16 is secured in a predetermined position relationship with the hollow body 15. Consequently, the indicator 26 also indicates the space relationship between the adjacent ends of the inner conduit 10 and the hollow tip 16. In this manner it is possible to know the size of the nozzle passage.

Another indicator 15^a is secured to the hollow body 15 and in conjunction with a graduated ring 16^a fixed on the hollow tip 16, is adapted to indicate the relative position of the tapered end portion 17.

An auxiliary hollow casing 28 is mounted upon the bottom extended end of the hollow tip 16. This auxiliary hollow casing 28 is formed with a plurality of openings 29. The casing 28 is used as a screen to prevent any larger material than the openings 29 to pass into the hollow tip 16 of the device.

A fluid under high pressure is forced into the horizontal arm 12^a of the elbow 12 and it will travel down into the hollow body 15. Then the fluid will reverse itself and be forced up through the nozzle between the tapered portions 11 and 17 and continue upwards through the inner conduit 10. The nozzle construction serves to produce suction in the hollow tip 16 and it is this suction which will draw up the material entering the hollow body 28. Several radial vanes 30 are mounted upon a hub portion 31 engaged on the lower end of the conduit 14. These vanes engage the inner wall of the outer conduit 14 for securely holding the inner conduit properly axially spaced in the outer conduit.

In Figs. 5 and 6 another embodiment of the invention has been disclosed which distinguishes from the prior form merely in the construction and relation of the parts. According to this form of the invention there is an inner conduit 35 which extends up through the vertical head of a T-connection 36. A fluid supply pipe 37 is connected with the side of the T-connection 36. A nut 38 is threadedly engaged on an extended portion of the inner conduit 35 and is adapted to abut the top end of the T-connection 36 for fixedly mounting the inner conduit.

The top end of the conduit 35 is provided with a valve 39. The bottom end of the conduit 35 has an inwardly turned upwardly extending portion 40 which tapers and which is cooperative with a tapered portion 41 on a hollow tip 42. This hollow tip 42 is mounted on the hollow body 43. A nut 44 is threadedly engaged on the tip 41 and acts against the hollow body 43 for locking these parts in position. The hollow body 43 is mounted upon an outer conduit 45 which is

connected with the bottom end of the T-connection 36.

The suction nozzle between the tapered portions 40 and 41 may be controlled by first loosening the nuts 38 and 44, then adjusting the inner conduit 35 and the hollow tip 42, and then resetting the nuts to hold the parts in their new positions.

In Fig. 7 another embodiment of the invention has been disclosed which distinguishes from the prior form in several respects. According to this form there is an inner conduit 46 which extends through the top of a hollow body 47. A nut 48 is threadedly mounted on an extended portion of the conduit 46 and is abuttable against the body 47 for locking the conduit in a fixed position relative to the body. An indicator 49 is mounted upon an extended end of the conduit 46 and acts upon a scale 50 imprinted on the hollow body 47 to indicate the relative positions of these parts and so indirectly indicate the size of the nozzle passage arranged between the lower end of the conduit 46 and a hollow tip 51. This hollow tip is threadedly mounted through the bottom of the hollow body 47. A nut 52 threadedly engages upon the tip and is abuttable against a portion of the hollow body 47 for fixedly holding the tip relative to the body.

A T-connection 52' is mounted on an intermediate portion of the conduit 46. A valve 53 is mounted on a top portion of the conduit 46. The T-connection 52' connects with a three-way valve 54. This valve is arranged in a pipe line 56 connected with the hollow body 47 and adapted to be connected with a supply of fluid under high pressure. This three-way valve 54 has a valve proper 54^a which may be turned so that the fluid coming down the pipe 56 instead of discharging into the hollow body 47 is transferred to the inner conduit 46. Or the valve proper 54^a may be placed so that the fluid passing through the pipe 56 discharges into the hollow body 47.

The side wall of the casing of the three-way valve 54 is broken away to illustrate the valve proper therein. A handle 58 is indicated, connected with the valve proper 54^a by which it may be moved from one to the other position. The purpose of the three-way valve is to control the passage of fluid through the device in a manner similar to that described in the patented invention previously referred to.

The main outlet valve 20^b enables the operation of the lower nozzle so that the water may pass through it in either direction. If this valve is open, the burrowing and lifting of material is done by suction created at the lower nozzle. If then the valve is closed, the direction of the water flow through the nozzle is reversed and the clearing of the nozzle is done by means of expelling the water. This promotes rapid operation and instantaneous clearing of undesirable matter.

In Fig. 8 another form of the invention has been disclosed which distinguishes from the prior form in the construction of the nozzle. According to this form of the invention there is a return conduit 60 formed with a bottom offset portion 61 adapted to engage into the mud, sand, gravel or the like which is being dredged. An upward directed nozzle passage 62 is associated with the pipe 60 coaxial with the top portion thereof and located at the top of the offset portion 61. A fluid supply pipe 63 is connected with the bottom of the nozzle 62. Fluid under pres-

sure which is forced downwards through the pipe 63 will pass upwards through the nozzle 62 and up along the pipe 60. This passage of the fluid will cause suction at the bottom offset portion 5 61. This suction will draw up the material to be dredged. The conduit 60 is shown provided with a valve 63^a by which the passage there-thru may be controlled. In other respects this 10 form of the invention is similar to those previously described.

In Fig. 9 another modified form of the invention is disclosed which is very similar to the form shown in Fig. 8, distinguishing merely in the fact that this device is provided with a nozzle 62' 15 which may be adjusted relative to the offset portion 61 of the vertical conduit 60. Specifically, the nozzle 62' is formed in a separate nozzle body which threadedly engages through a portion 60^a in the side wall of the conduit 60. A nut 65 20 threadedly engages on the nozzle body 62' and is adapted to abut a portion of the conduit 60 for holding the nozzle body fixed, as adjusted. The dot and dash lines 62'' indicate one adjusted 25 position of the nozzle body. It should be realized that the nozzle body 62' may be moved upwards or downwards to various positions. A change of the position of the nozzle body will control the relative positions of the nozzle to the conduit 60 and thus the efficiency of the suction 30 conduit 60 through the conduit 61.

It is to be understood that my dredge apparatus can be operated not only by water under pressure, but also by compressed air, steam, etc.

While I have illustrated and described the preferred embodiments of my invention, it is to be understood that I do not limit myself to the precise constructions herein disclosed and the right is reserved to all changes and modifications 35 coming within the scope of the invention as defined in the appended claims.

Having thus described my invention, what I claim as new, and desire to secure by United States Letter Patent is:

1. In a dredge, a valve controlled vertical inner conduit having an internally upwardly and inwardly tapered bottom end, an elbow connection having a portion of said inner conduit engaged through the vertical arm thereof, a nut fixedly mounted on said inner conduit and threadedly engaged into the upper end of said vertical arm for holding said inner conduit in various adjusted positions with relation to said elbow, an outer conduit engaged coaxially over said inner conduit and fixedly engaged into the bottom end 50 of said vertical arm, a hollow body mounted on the bottom end of said outer conduit, a hollow tip 55 adjustably mounted coaxially through the bottom of said hollow body and having a tapered top end cooperative with the tapered bottom end of said inner conduit for forming a suction nozzle, a nut threadedly engaged on an extended portion of said tip and engageable against the bottom end of said hollow body for holding said tip in position with relation to the bottom end of 60 said inner conduit, a scale on the vertical arm of said elbow, and an indicator mounted upon the extended portion of said conduit and cooperative with said scale for indicating the position of the bottom end of said inner conduit with 65 relation to the adjacent end of said tip and so register the operative size of said nozzle, said indicator comprising a collar adjustably mounted on the extended end of said inner conduit, and an indicator finger mounted on said collar and having its registering tip extending longitudinally of 70 the axis of said conduits and over the top edge of said elbow to register on said scale, said scale having its markings longitudinally of 75 the axis of said conduits in substantially the same plane as said registering tip of said indicator finger.

the axis of said conduits and over the top edge of said elbow to register on said scale.

2. In a dredge, a valve controlled vertical inner conduit having an internally upwardly and inwardly tapered bottom end, an elbow connection having a portion of said inner conduit engaged through the vertical arm thereof, a nut fixedly mounted on said inner conduit and threadedly engaged into the upper end of said vertical arm for holding said inner conduit in various adjusted positions with relation to said elbow, an outer conduit engaged coaxially over said inner conduit, a hollow tip adjustably mounted coaxially through the bottom of said hollow body and having a tapered top end cooperative with the tapered bottom end of said inner conduit for forming a suction nozzle, a nut threadedly engaged on an extended portion of said tip and engageable against the bottom end of said hollow body for holding said tip in position with relation to the bottom end of said inner conduit, and an indicator finger mounted on said inner conduit and extending over a scale mounted on a stationary part to indicate the relative position of the inner conduit relative to the said hollow tip.

3. In a dredge, a valve controlled vertical inner conduit having an internally upwardly and inwardly tapered bottom end, an elbow connection having a portion of said inner conduit engaged through the vertical arm thereof, a nut fixedly mounted on said inner conduit and threadedly engaged into the upper end of said vertical arm for holding said inner conduit in various adjusted positions with relation to said elbow, an outer conduit engaged coaxially over said inner conduit and fixedly engaged into the bottom end of said vertical arm, a hollow body mounted on the bottom end of said outer conduit, a hollow tip adjustably mounted coaxially through the bottom of said hollow body and having a tapered top end cooperative with the tapered bottom end of said inner conduit for forming a suction nozzle, a nut threadedly engaged on an extended portion of said tip and engageable against the bottom end of said hollow body for holding said tip in position with relation to the bottom end of said inner conduit, a scale on the vertical arm of said elbow, and an indicator mounted upon the extended portion of said conduit and cooperative with said scale for indicating the position of the bottom end of said inner conduit with relation to the adjacent end of said tip and so register the operative size of said nozzle, said indicator comprising a collar adjustably mounted on the extended end of said inner conduit, and an indicator finger mounted on said collar and having its registering tip extending longitudinally of the axis of said conduits and over the top edge of said elbow to register on said scale, said scale having its markings longitudinally of the axis of said conduits in substantially the same plane as said registering tip of said indicator finger.

4. In a dredge, a valve controlled vertical inner conduit having an internally upwardly and inwardly tapered bottom end, an elbow connection having a portion of said inner conduit engaged through the vertical arm thereof, a nut fixedly mounted on said inner conduit and threadedly engaged into the upper end of said vertical arm for holding said inner conduit in various ad-

justed positions with relation to said elbow, an outer conduit engaged coaxially over said inner conduit and fixedly engaged into the bottom end of said vertical arm, a hollow body mounted on the bottom end of said outer conduit, a hollow tip adjustably mounted coaxially through the bottom of said hollow body and having a tapered top end cooperative with the tapered bottom end of said inner conduit for forming a suction nozzle, a nut threadedly engaged on an extended portion of said tip and engageable against the bottom end of said hollow body for holding said tip in position with relation to the bottom end of said inner conduit, a scale on the vertical arm of said elbow, and an indicator mounted upon the extended portion of said conduit and cooperative with said scale for indicating the posi-

tion of the bottom end of said inner conduit with relation to the adjacent end of said tip and so register the operative size of said nozzle, said indicator comprising a collar adjustably mounted on the extended end of said inner conduit, and an indicator finger mounted on said collar and having its registering tip extending longitudinally of the axis of said conduits and over the top edge of said elbow to register on said scale, said collar, comprising a pair of semi-circular collar sections engaging around said inner conduit at right angles to the axis thereof, out turned ends formed on the ends of said collar sections, and screws threadedly engaged through said outturned ends for clamping said collar in various adjusted positions on said conduit.

BERT O. GODFREY.
